DESIGN FOR A CONTAINER CAP

Georges Wilmet, New York, N. Y., assignor to Armstrong Cork Company, Lancaster, Pa., a corporation of Pennsylvania

Application August 24, 1936, Serial No. 64,535

Term of patent 7 years

To all whom it may concern:

Be it known that I, Georges Wilmet, a citizen of Belgium, residing in New York, county of New York, and State of New York, have invented a new, original, and ornamental Design for Container Caps, of which the following is a specification, reference being had to the accompanying drawing, forming a part thereof.

The figure is a perspective view of a container cap, showing my new design.

I claim:

The ornamental design for a container cap as shown.

GEORGES WILMET.
